UNITED STATES PATENT OFFICE.

BELA MARTON KISH, OF DUQUESNE, PENNSYLVANIA.

DESIGN FOR A SIDEBOARD.

50,067.

Specification for Design.

Patented Dec. 19, 1916.

Application filed September 20, 1916. Serial No. 121,323. Term of patent 7 years.

To all whom it may concern:

Be it known that I, BELA MARTON KISH, a subject of the King of Hungary, residing at 116 East Duquesne avenue, Duquesne, in the county of Allegheny and State of Pennsylvania, have invented a new, original, and ornamental Design for Sideboards, of which the following is a specification, reference being had to the accompanying drawing, forming part thereof.

I claim:

The ornamental design for a sideboard as shown.

BELA MARTON KISH.
